CLAIM

The ornamental design for a wick for candle, as shown and described.

DESCRIPTION

FIG. 1 is a front elevational view of an embodiment of a wick for candle;

FIG. 2 is a rear elevational view thereof;

FIG. 3 is a right side elevational view thereof, the left side elevational view being the same as the right side elevational view shown;

FIG. 4 is a perspective view thereof in the environment of an unclaimed candle; and,

FIG. 5 is a top plan view thereof in the environment of an unclaimed candle.

The broken lines shown in the figures are for the purpose of illustrating portions of a wick or candle that form no part of the claimed design.
